THOMAS S. HOMANS, OF HEMPSTEAD, NEW YORK, ASSIGNOR TO INTERTYPE CORPORATION, OF BROOKLYN, NEW YORK, A CORPORATION OF NEW YORK.

DISTRIBUTER FOR TYPOGRAPHICAL MACHINES.

1,334,098.

Specification of Letters Patent. Patented Mar. 16, 1920.

Application filed November 17, 1919. Serial No. 338,613.

To all whom it may concern:

Be it known that I, THOMAS S. HOMANS, a citizen of the United States, residing at Hempstead, in the county of Nassau and State of New York, have invented new and useful Improvements in Distributers for Typographical Machines, of which the following is a specification:

The present invention relates to improvements in typographical machines, and more especially to those of the linotype class using matrices provided with teeth by which they are supported, while they travel along a distributor bar, and lugs on their corners. 10 The primary object of the invention is to provide novel and improved means for handling the so-called sorts or pi character matrices which do not belong in the magazine which is in use in the machine, where- 15 by these sorts or pi character matrices will all be dropped from the same point in the length of the distributor, although these matrices may vary greatly in thickness and some of them may be of considerable thick- 20 ness and bear large type characters such as those used for advertising or display purposes. By causing all of the sorts or pi character matrices to discharge at the same point in the length of the distributor, notwithstanding the variations in the thickness 25 of such matrices, the reception of such matrices by a tube, chute or equivalent means for conveying them to a pi stacker, or other suitable collecting device, is greatly 30 facilitated, and liability of clogging or catching of such matrices while on their way to the pi stacker or collecting device, is avoided.

To these and other ends, the invention consists in certain improvements, combinations and arrangements of parts, all as will be hereinafter more fully described, the features of novelty being pointed out particularly in the claims at the end of the specification.

In the accompanying drawing:

Figure 1 is a perspective view of one end of the distributor of a line casting machine of the linotype class, the same being viewed from the rear and equipped with the means provided by the present invention for causing dropping of the sorts or pi character matrices from the distributor into the chute by which they are conveyed to a pi stacker or other collecting device, and

Fig. 2 represents an elevation of the parts

shown in Fig. 1, as viewed from the left in said Fig. 1.

Similar parts are designated by the same reference characters in the several views. 60

The present invention is applicable generally to typographical or line casting machines of the classes in which the slugs are cast from matrices which circulate through the machine. In the present instance, the 65 invention is shown applied to a machine of the linotype class, using matrices having teeth in their upper edges for supporting the matrices while they travel along the distributor bar, and lugs which project from 70 the corners of the matrices. The preferred embodiment of the invention is shown and will be hereinafter described in detail, but it is to be understood that the invention is not restricted to the precise construction 75 shown as equivalent constructions are contemplated and will be included within the scope of the claims.

The purpose of the invention is to provide means for handling more advantageously 80 the sorts or pi character matrices which are not carried in the matrix magazine which is in use in the machine, or are delivered to a tube or chute through which they drop by gravity into a suitable receptacle from 85 which the operator can set them into a composed line, by hand. These so-called sorts or pi character matrices bear type characters of various sizes and kinds, and consequently these matrices vary in thickness, 90 and furthermore, recent developments in the art have brought into use matrices which are so thick that it has been difficult to properly handle these thick matrices and also the thin ones, owing to the fact that heretofore 95 these sorts or pi character matrices have been dropped irrespective of their size or dimensions from the distributor bar into a chute or tube, which chute or tube was made sufficiently large to accommodate the sorts 100 or pi character matrices having large or thick bodies, which resulted in twisting and consequent clogging of the relatively thinner sorts or pi character matrices when the latter dropped into the same chute. These 105 difficulties are avoided by the present invention, according to which the sorts or pi character matrices are guided by their lugs instead of their bodies as heretofore, while passing through the chute, to accomplish 110 which the present invention provides novel and improved means whereby the sorts or pi

character matrices at the moment they drop from the distributor are properly alined or positioned to enter the chute, irrespective of the variations in the thicknesses of these matrices. By this construction and arrangement correct entrance of all the sorts or pi character matrices into the chute or tube is insured, notwithstanding great variations that may exist in the thicknesses of the bodies of these matrices, and the matrices, while passing through the chute or tube, are guided by their projecting lugs, and hence twisting and consequent clogging of the matrices in the chute is prevented.

In the present embodiment of the invention 1 represents a portion of the distributor bar having combination teeth 2 formed on its lower convergent edges, these combination teeth being similar to those commonly used in machines of the linotype class to co-operate with the tooth combinations formed in the notches in the upper ends of the matrices, whereby the matrices are supported while they travel along the distributor bar and are released from the distributor bar when they reach points in line with the entrances to their respective channels in the magazine. The matrices are advanced along the distributor bar in a direction from the right and toward the left in Fig. 1 by distributor screws 4 which engage the lugs or ears which project from the corners of the matrices, as will appear from Fig. 2. The advance of the matrices by the distributor screws and the dropping of the matrices at the proper point in the length of the distributor bar in order that the matrices belonging in the magazine in use in the machine may be caused to enter the respective channels in the magazine, takes place in a manner well known to those familiar with machines of the linotype class.

The sorts or pi character matrices are similar in their general outline to the matrices which are stored in the magazine, that is they each have a body, lugs projecting from the corners of the body, and teeth formed in the upper end of the matrix, but these teeth do not form combinations as is the case with the matrices which belong in the magazine, but on the contrary, each of the sorts or pi character matrices is provided with a full set of teeth. Also, the pi character matrices vary very considerably in the thickness of their bodies. For example, M' , M^2 and M^3 represent three sorts or pi character matrices having bodies which vary substantially in thickness. By leaving all of the teeth 3 in the sorts or pi character matrices, these matrices will be caused to traverse the distributor bar to the extreme end of its toothed portion. In the case of the matrices M' and M^2 , it is to be observed that these matrices which have relatively thick bodies have their combination or sup-

porting teeth formed on the righthand side of the body in Fig. 1 and the projecting lugs m on the lefthand side of the body, this being the usual way of making matrices, and it would be impracticable to alter the relative location of these characteristic parts of the matrices, owing to the co-operation between these parts of the matrices and parts of the machine through which the matrices circulate.

75

According to the present invention the distributor bar is provided near its extreme lefthand end in Fig. 1, with a complete set of teeth 2^a to co-operate with the complete sets of teeth in the sorts or pi character matrices, these teeth 2^a being located beyond the usual combination teeth 2 and they receive the sorts or pi character matrices after the latter pass off or beyond the combination teeth 2, the continued advance of the sorts or pi character matrices being effected by the distributor screws 4 which are of a sufficient length to accomplish this. The teeth 2^a are relatively short in length and they terminate at the point occupied by the matrix M^2 so that this matrix has just left the supporting teeth 2^a . Obviously if this matrix M^2 , or one of similar body thickness were allowed to drop from the distributor at this point, and the following thin-bodied matrix M^3 were permitted to drop at the same point, that is the point where the teeth of these matrices reach the end of the supporting teeth 2^a , the lugs m of these two matrices would fall in substantially different vertical positions. In order to enable the sorts or pi character matrices to be guided by their lugs while passing through the chute, and thus avoid twisting and consequent clogging of these matrices, means is provided for insuring the dropping of all of the sorts or pi character matrices so that their lugs will be in the same vertical plane. Preferably and as shown, a pair of rails 5 is provided, these rails performing the function of supporting the sorts or pi character matrices by their upper lugs m after the teeth in these matrices have left or passed beyond the end of the supporting teeth 2^a of the distributor bar, the rails being located in parallelism with and at opposite sides of the lower edge of the distributor bar and at a level which permits the upper lugs of the matrices to pass over and to eventually come to rest upon the upper edges of these rails. In this way the matrices when disengaged from the supporting teeth 2^a of the distributor bar become supported by the upper lugs of the matrices which rest upon the upper edges of the rails and as the distributor screws still engage these matrices, the advance of such matrices continues until the upper lugs which support the matrices on the rails reach the lefthand ends of the rails, whereupon the matrices drop into the chute 130

6. In this way all of the sorts or pi character matrices are caused to drop from the distributor when the lugs of the matrices reach a predetermined vertical plane which is 5 constant, notwithstanding variations in the thicknesses of the matrices and consequent variations in distance between the supporting teeth of the matrices and their lugs. The chute 6 is formed with grooves 7 which 10 are alined with the discharge ends of the rails 5, as a result of which the lugs on the matrices dropping from the rails 5 enter these grooves and the matrices are thereby guided by their lugs while passing through 15 the chute, the bodies of the relatively thick matrices projecting without obstruction to the outside of the chute, as illustrated by the matrix M'. The rails 5 are preferably attached to the distributor bar 1 by brackets 20 8, the brackets being secured by the screws 9, or other suitable means, to the distributor bar, this arrangement being preferable as it enables the distributor bar and the rails 5 to be handled as one part.

25 By supporting the matrices by the rails on which the upper laterally projecting lugs of the matrices rest, after the distributing teeth of the matrices have become released or disengaged from the teeth on the distributor bar, the lugs of the matrices determine the point at which each matrix will 30 drop into the chute, and inasmuch as these lugs are located similarly on all of the matrices although the thicknesses of the bodies 35 of the matrices may vary considerably, the matrices will all drop when their lugs reach a predetermined constant point, and hence correct reception of these matrices by the chute is always insured. Preferably the 40 lefthand end (Fig. 1) of the distributor bar is continued somewhat beyond the point where the matrix-supporting teeth terminate, but this continued portion of the bar is without teeth, in order that it may serve 45 to steady the matrices while they are advanced along the rails 5 without, however, interfering with the dropping of the matrices into the chute when their supporting lugs reach the ends of the rails.

50 I claim as my invention:—

1. In a typographical machine having a toothed distributor bar and adapted to use pi matrices having lugs projecting from their bodies, means for supporting such pi 55 matrices by their lugs when they become disengaged from the distributor bar, whereby they are conducted to a common point of distribution.

2. In a typographical machine having a 60 toothed distributor bar and using matrices having bodies of different thicknesses with full sets of distributor teeth at one side of the body adapted to engage and to be supported by the teeth of the distributor bar in 65 passing the various combinations thereon to

the end of the bar, said matrices also having lugs projecting outwardly at the opposite side of the body, means for supporting the different matrices by their projecting lugs after the teeth of the matrices become 70 disengaged from the teeth of the distributor bar and for discharging the matrices so supported when their lugs reach a predetermined plane.

3. In a typographical machine having a 75 toothed distributor bar and using pi matrices having full sets of teeth to engage and support the matrices by the teeth of the distributor bar in passing the various combinations thereon to the end of the bar, said pi 80 matrices also having lugs projecting from their bodies, rails located adjacent to the terminus of the matrix-supporting teeth on the distributor bar to engage the lugs and thus support such pi matrices after they 85 have become disengaged from the teeth on the distributor bar.

4. In a typographical machine having a toothed distributor bar for supporting matrices to travel thereon and using matrices 90 having teeth to engage the teeth on the distributor bar and also having lugs projecting from their bodies, a chute located beyond the matrix-releasing end of the teeth on the distributor bar to receive and guide such 95 matrices by their projecting lugs, and means located between the matrix-releasing end of the distributor-bar teeth and the chute for supporting the matrices by their projecting lugs after their release from the distributor 100 bar and for discharging them into the chute when the lugs of the matrices reach a predetermined constant position.

5. In a typographical machine having a toothed distributor and using matrices having bodies of different thicknesses with lugs projecting from the body at one side and distributor teeth at the opposite side of the body adapted to engage and support the matrices by the teeth of the distributor bar, 110 a matrix chute to receive and guide the matrices by the projecting lugs thereof, rails arranged longitudinally of the distributor bar beyond the matrix-releasing end of the teeth thereof to support the matrices by their projecting lugs after the teeth of the matrices have become disengaged from the teeth of the distributor bar, the matrices being adapted to discharge from said rails into 115 said chute when the lugs of the matrices reach a predetermined position, and means for advancing the matrices along the distributor bar and also along said rails.

In testimony whereof I have hereunto set my hand in presence of two subscribing witnesses. 125
